UNITED STATES PATENT OFFICE

CHARLES O. PELLETIER, OF OAKLAND, CALIFORNIA.

CONCEALABLE BED.

1,123,363.

Specification of Letters Patent.

Patented Jan. 5, 1915.

Application filed August 20, 1913. Serial No. 785,695.

To all whom it may concern:

Be it known that I, CHARLES O. PELLETIER, a citizen of the United States, residing at Oakland, in the county of Alameda and State of California, have invented new and useful Improvements in Concealable Beds, of which the following is a specification.

The object of the present invention is to provide a concealable bed of improved construction, which, when not in use can be concealed in a closet located anywhere in relation to the sleeping room or rooms, and which can be removed from said closet and transported to the place intended to be used and there turned in any direction to be opened and set on the floor. With this object in view I mount the frame of the bed on an upright member fixed on a carriage provided with casters or rollers, the mounting being in such a way as to permit said bed frame to turn around said upright member through the whole circle.

For a clearer description of this invention I refer to the accompanying drawings, which illustrate some of the ways of application of my improvement and in which—

Figure 1 is a plan of my device, Fig. 2 a vertical sectional elevation of the same, Fig. 3 a plan of a modification showing the device suspended from an overhead rail, and Fig. 4 a side elevation of the same.

1 indicates the floor of a sleeping room, 2 that of a closet, and 3 that of a sleeping porch.

4 and 5 indicate the walls, and 6 and 7 the doors, between the closet and the room and sleeping porch respectively.

On the floor 2 of the closet are secured a pair of rails 8 extending in the direction between the room and the porch, each rail being in the form of a channel iron, one side of which rests upon the floor, and the middle portion of which is vertical, while the other side is above the floor. The flanges of the channel iron extend outwardly from the middle portion, and over said rails travels a carriage 9, having at the sides depending arms 11, from the lower ends of which extend toward one another shafts 12, carrying grooved wheels 13, which run in said channel irons. Upon a corner of said carriage next the door 6 of the room is erected a post 14, which passes through upper and lower bearings in the ends of arms 15 of a yoke-shaped frame 16 rigidly secured at its middle to a bed frame 17. A folding bed is

made to fit in the inside of said bed frame, and is hinged near the bottom and properly clamped at the top, so as to be readily opened, and brought to a horizontal position, when wanted for use, and to be easily folded up again, when not in use.

In using the bed in the sleeping room 1, the carriage 9 is moved toward said room until the post 14 abuts against a stop 18 on the jamb of the door of the room. The bed is then swung on the post 14 through the doorway to the position shown by dotted lines in Fig. 1, when the bed will be ready to be lowered onto the floor for use, and when so lowered it will extend from the wall 4 inward toward the room. In using the bed on the sleeping porch 3 the carriage 9 is transported over the rails 8 (or over the floor, when no rails are used) to the place, where the bed is to be opened, and there the bed frame 17 is turned around the vertical post 14 to such an angle, as to bring the bed when lowered onto the floor to face the direction wanted. To move the device from the porch 3 to the sleeping room 1 or vice versa from the sleeping room onto the sleeping porch 3, it is best to keep the bed frame 17 on the carriage 9 in the position shown in full lines in Fig. 1, as in this position the bed can pass through narrow doorways.

When not in use the bed is transported to the closet and there the bed frame 17 may be left in the same position in relation to the carriage 9, as it had, when brought through the door, provided the depth of the closet will permit it; otherwise it may be turned around the vertical post 14, as it gradually passes through the narrow door of the closet and be brought finally to a position at right angles to that shown in Fig. 1.

Should the closet be like the one shown, the bed frame 17, after the carriage 9 is brought to the middle of the closet, is turned around the upright post 14 through an angle of 180°, when said frame will be entirely at the left of the closet, leaving the passage between the doors unobstructed; the channelled rails 8 engaging the rollers 12 of the carriage 9 will prevent the whole structure from tilting, should the bed be especially heavy and the door narrow, requiring a correspondingly narrow carriage.

In the modification of the invention shown in Figs. 3 and 4, I employ a carriage 21 suspended from a pair of grooved rollers 22, which travel in a channel 23 in a bar 24, one

end of which is secured to the wall 4, said bar extending through an opening 25 in the wall 5 above the doorway of the door 7, and the other end being connected to a post 26 suspended from above over the sleeping porch. From said carriage depends an upright or hanger 27, on which is pivotally mounted, by arms 28, 29, at top and bottom, the bed frame 31.

10 To maintain the hanger in a vertical position, there are erected upon the carriage 21 posts 32, which carry grooved rollers 33, which travel beneath a rim or flange 34, rigidly connected with the bar 24. As an 15 additional means for this purpose, the lower end of the hanger may move in a channel iron 35 secured to the floor.

Having thus described my invention, what I claim as new and desire to secure by Letters Patent is:

1. The combination of a carriage, adapted to move in a horizontal plane, an upright member rigidly mounted on said carriage to form a stable, upright, traveling column, 25 arms spaced some distance one above the other, pivoted to said column, so as to swing in a horizontal plane, and a bed frame containing a folding bed, rigidly secured to

said arms and maintained by them permanently in an upright position.

2. The combination of a carriage, adapted to move in a horizontal plane, an upright member rigidly mounted on said carriage to form a stable, upright, traveling column, a bed frame containing a folding bed, supported by and pivoted to said column, so as to turn around the latter for a full circle, maintaining all the time an upright position.

3. The combination of a carriage, rollers supporting said carriage, stationary rails of a channel cross-section, adapted to engage said supporting rollers, so as to guide said carriage in a horizontal plane, an upright member rigidly mounted on said carriage to form a stable, upright, traveling column, and a bed frame, containing a folding bed, pivoted to said column, so as to turn around the latter, remaining permanently in an upright position.

In testimony whereof I have hereunto set my hand in the presence of two subscribing witnesses.

CHARLES O. PELLETIER.
